UNITED STATES PATENT OFFICE.

SAMUEL E. DRAYER, OF CLEVELAND, OHIO, ASSIGNOR TO THE GUIDE MOTOR LAMP MANUFACTURING COMPANY, OF CLEVELAND, OHIO, A CORPORATION OF OHIO.

SIDE LAMP FOR AUTOMOBILES.

Application filed April 19, 1927. Serial No. 184,912.

This invention relates generally to lamps for automobiles and more particularly to a novel construction of side lamp.

The object of the invention is to provide an exceedingly cheap, simple and efficient means of fastening or securing the glass and door or frame to the body portion of the lamp and also to so construct and arrange these parts as to provide for the quick and easy displacement or replacement of the front in case it is necessary or desirable to replace the bulb within the lamp.

Another object of the invention is to so construct the front or door that all of the parts are connected together so that when said front or door is removed from the body portion or housing for the purpose of replacing the bulb the various parts of the front or door will not become disassociated; and a still further object is to so construct the various parts of the front or door that in case said front or door should become accidentally disconnected from the body portion or housing the danger of breakage will be reduced to a minimum due to the fact that the glass is securely held in place within the circular frame or door.

Another object of the invention is to so construct the various parts that when the complete assemblage is effected all of the parts will be held firmly together and rattling thereby prevented.

With these various objects in view the invention consists in the novel features of construction and arrangement, all of which will be fully described hereinafter and set forth in the appended claims.

In the drawings forming a part of this specification, Fig. 1 is a sectional view partly in elevation showing a side lamp embodying one form of my invention; Fig. 2 is a face view of the body portion or housing, the front or glass door being removed therefrom; Fig. 3 is a rear view of the front or glass door; Fig. 4 is a detail plan view of the spring ring or washer; Fig. 5 is a detail sectional view on the line 5—5 of Fig. 2; and Fig. 6 is a detail view on the line 6—6 of Fig. 3; Fig. 7 shows a modification of the ring.

In carrying out my invention I employ a body portion or housing 10 in which is arranged the incandescent lamp bulb 11. The body portion or housing may be of any

desired shape so long as the front thereof is circular and open as indicated. The edge of the body portion or housing 10 is provided with two oppositely disposed outwardly projecting lugs or fingers 12 the purpose of which will appear hereinafter. 13 indicates the glass which is preferably translucent and is carried by a channeled ring or frame 14 the inner edge 15 of said ring or frame engaging the outer face of the glass adjacent the outer edge thereof as most clearly shown in Fig. 1. The outer edge of this channeled ring is rolled inwardly as indicated at 16 and this rolled in edge is formed with a single notch 17 as most clearly shown and adjacent to this notch 17 the rolled in edge is also provided with indentations 18 and 19, the indentation 19 being slightly deeper than the indentation 18 for the purpose hereinafter described. In order to hold the glass 13 in the channeled ring or frame 14 I employ a flat spring ring or washer 20 divided at 21 and this flat spring ring or washer can be threaded into the channeled ring or frame by inserting one end in the notch 17 and then working the ring around 25 until the entire ring has been threaded into the channeled ring or frame, its inner edge contacting with the rear face of the glass adjacent its outer edge while its outer edge will be confined by the rolled in edge 16 of 30 the channeled ring or frame. The parts thus connected, namely, the glass, the channeled ring and the spring ring or washer constitute a door front of the lamp that is adapted to be fitted within the body portion 35 or housing. In order to do this it is only necessary to insert one of the lugs 12 into the rolled in edge 16 and bring the other lug 12 opposite the notch 17 and then by pressing rearwardly and turning the channeled ring or frame both of the lugs will be entered into the channeled ring and the front or door securely connected to the body portion or housing of the lamp and in bringing these parts together it will be noted that 40 the outer rear portion of the spring ring or washer contacts with the front edge of the body portion or housing and that pressure is consequently transmitted through the glass thereby holding all of the parts securely together and preventing rattling.

When the channeled ring or frame is turned for the purpose of securing the door

or front to the body portion or housing the movement of the frame is continued until the lug or finger 12 which has been fitted into the notch 17 is brought between the 5 indentations 18 and 19 and inasmuch as the indentation 18 is not quite so deep as the indentation 19 it will be possible to force the lug past the indentation 18 and the indentation 19 will stop said lug thereby holding 10 the same between the indentations 18 and 19 and securely locking the channeled ring or frame with its contained parts in locked relation with the body portion or housing and rattling of the parts thereby 15 prevented.

It will thus be seen that I provide a cheap and simple device in which the door or front is entirely self contained, that is, the glass and frame and securing washer are all connected together so that the front as a whole can be detached and removed from the body portion or whenever it is desired to replace the bulb and all danger of the parts of the front becoming disassociated is overcome. 20 Furthermore, when all the parts are assembled as shown in Fig. 1, all of the parts cooperate to produce a tight connection and thereby completely eliminate the danger of rattling while in use.

30 Instead of a flat spring ring such as shown in Figs. 1, 2, 3 and 4, I may employ a wire ring bent as shown so that contact is had with the edge of the glass and also the in-rolled edge 16.

35 Having thus described my invention, what I claim is:—

1. As a new article of manufacture, a lamp comprising a body portion having oppositely disposed outwardly extending lugs, 40 a channeled ring having a notch, a glass front, and a flat ring interposed between the forward edge of the body portion and the rear edge of the glass, the inner edge of the channeled ring engaging the outer face of 45 the glass and the outer edge being held in

locked relation with the edge of the body portion.

2. In a lamp, a channeled ring having a notch in its outer edge, a glass contacting with the inner edge of said channeled ring, a flat divided ring threaded into the channeled ring and contacting with said ring and glass, and a body portion having oppositely disposed lugs adapted for engagement with the channeled ring carrying the glass 55 and split ring as set forth.

3. In a lamp, a glass front, a channeled ring for holding said glass, the inner edge of the ring contacting with the forward face of said glass, the outer rolled edge of said 60 channeled ring having a notch, a flat divided spring ring threaded into the channeled ring at the rear of the glass front, the inner edge of the said spring ring contacting with the rear face of the glass at the outer edge 65 thereof, and a body portion having oppositely disposed lugs adapted to engage the rolled outer edge of said channeled ring, the rear face of the spring ring contacting with the forward edge of the body portions 70 when the parts are held in locked relation.

4. In a lamp, a glass front and channeled ring for carrying the same, the inner edge of said ring contacting with the outer face of the glass near the outer edge thereof, the outer edge of said ring being rolled inwardly and provided with a notch and a plurality of spaced indentations, a flat divided spring ring threaded into the channeled ring and contacting at its inner edges 75 with the rear face of said glass near the outer edge, and a body portion having oppositely disposed outwardly projecting lugs adapted to enter the rolled edge of the channeled ring and hold the parts together, one of said lugs fitting between the indentations in the rolled edge, as set forth.

In testimony whereof, I hereunto affix my signature.

SAMUEL E. DRAYER.
